CLAIM

The ornamental design for a brew basket, as shown and described.

DESCRIPTION

FIG. 1 is a top perspective view of a brew basket showing my new design;

FIG. 2 is a bottom perspective view thereof;

FIG. 3 is a left side view thereof;

FIG. 4 is a front view thereof;

FIG. 5 is a right side view thereof;

FIG. 6 is a rear view thereof;

FIG. 7 is a top view thereof; and,

FIG. 8 is a bottom view thereof.

The dot-dash broken lines illustrate structure or features which form no part of the claimed design.

1 Claim, 7 Drawing Sheets(56)
